UNITED STATES PATENT OFFICE

105,511

DESIGN FOR A FLOOR LAMP

Bayard C. Blackmore, Winchester, Calif.

Application May 28, 1937, Serial No. 69,613

Term of patent 7 years

To all whom it may concern:

Be it known that I, Bayard C. Blackmore, a citizen of the United States, residing at Winchester, in the county of Riverside and State of California, have invented a new, original, and ornamental Design for a Floor Lamp, of which the following is a specification, reference being had to the accompanying drawing, forming part thereof.

The figure is a perspective view of a floor lamp, showing my new design.

The opposite side of the article is substantially the same as the side shown in the drawing.

I claim:—

The ornamental design for a floor lamp as shown and described.

BAYARD C. BLACKMORE.
